UNITED STATES PATENT OFFICE.

EWEN A. CLARK, OF REVERE, MASSACHUSETTS.

TORPEDO-NETTING.

1,260,256.

Specification of Letters Patent. Patented Mar. 19, 1918.

Application filed October 12, 1914, Serial No. 866,260. Renewed January 10, 1917. Serial No. 141,693.

To all whom it may concern:

Be it known that I, EWEN A. CLARK, a citizen of the United States, and a resident of Revere, in the county of Suffolk and

5 Commonwealth of Massachusetts, have invented certain new and useful Improvements in Torpedo-Nettings, of which the following is a full, clear, and exact specification.

10 This invention relates to nettings designed to protect warships against destruction by torpedoes. The type of netting thus far used is open to the objection that, being stationary, it may be cut by a submarine 15 and a torpedo projected through the opening; or a torpedo set with a time-fuse may be used to clear away sufficient of the netting to permit the passage of others unimpeded.

20 The object of this invention is the construction of one or more traveling nettings operated from within the warship, and adapted by its motion to prevent its being cut by hostile craft; while a hole blown 25 through it at one part is replaced by the traveling uninjured sections of the remainder of the netting.

Referring to the drawings forming part 30 of this specification, Figure 1 is a plan view of a battleship equipped with a movable netting embodying my improvements. Fig. 2 is a detail face view of a portion of the netting. Fig. 3 is a transverse sectional view of the netting showing its operating 35 mechanism. Fig. 4 is a cross section of a battleship showing the netting carried thereby. Fig. 5 is a perspective view of a part of the netting.

The reference numeral 1 designates a 40 warship of any desired type having my movable netting or shield applied thereto. The latter is supported and actuated by several arms 2 having pulleys at their outer ends and also at an intermediate point of 45 their length, as shown in Figs. 1 and 3. I prefer to employ two movable nettings and one stationary netting, the latter between the others and the surface of the steamship, the movable nettings being adapted for 50 travel in opposite directions, but each netting being endless and embracing the entire vessel.

The outermost netting 4 is composed of vertical rods 5 attached near their top and 55 bottom ends to chains 7, 8 which engage the sprocket wheels 9, 10 carried by shafts 11,

12. These shafts have bearings within the strong hollow arms 2, and are rotated by power received from the vessel, as from electric motors 13 (Fig. 1). Between the 60 rods are located several horizontal lines of links 14, each link being formed with an eye 15 at each end (Fig. 5) penetrated by the rods, and kept in place thereon by sections of tubing 16.

65 For retaining the chains 7, 8 in place upon the wheels 9, 10, idler wheels 17 are provided (Figs. 2 and 3), and to connect the rods 5 with the chains in the grooves 19 of said wheels, each rod is formed with a 70 short arm 20 (Fig. 5) having an eye 21 composing one link in the chain.

I prefer to give each rod 5 an upward extension 22 hinged thereto to permit its swinging toward the side of the vessel, as 75 at 23, and adapted to yieldingly return to its normal vertical position, as by the counterweight 24.

A similar arrangement of chains 7, 8 and 80 rods and links 5, 14, is disposed a spaced distance from the netting 4, and composing a netting 25 designed to travel about the vessel in the opposite direction to the netting 4. To accomplish this, the chain 7 engages the under periphery of the pulley or 85 sprocket wheel 9' and the chain 8 the upper periphery of the pulley or sprocket wheel 10'; since the chains of the netting 4 engage the opposite points of their pulleys 9, 10. By rotating the shafts 11 and 12 in 90 opposite directions, the two chains of the netting 4 will travel in one direction, and the two chains of the netting 25 will travel in the opposite direction.

I prefer to support a stationary netting 95 26 between the arms (Figs. 1 and 3) a short distance between the inner netting 25 and the ship's side, and to attach a fine meshed netting 27 to the outer movable netting 4, as shown in Fig. 3.

100 The arms 2 are pivoted at 29 to swing vertically, and are supported substantially horizontal by cables 30 attached to the upper arms at 31 and to the side of the vessel at an elevated point.

105 A netting 32 may be suspended beneath the vessel (Fig. 4) in order to guard the under surface thereof.

The operation of the invention is as follows: The nettings 4 and 25 being made to 110 continuously travel horizontally about the warship, a torpedo fired at the vessel and

reaching the outermost netting head on, will instantly have its head carried laterally, and under the effect of its own propeller and the movement of the netting, it will be carried along with the netting until the sharp bend at either end of the vessel is reached, when it will abandon the netting and go sailing off elsewhere.

If the torpedo penetrates the outer netting sufficiently to enter the next one 25, the turning effect on the torpedo is even quicker than before, and it is still more certainly prevented from reaching the vessel.

The innermost or stationary netting 26 is provided to entangle and stop the torpedo in case the movable ones are disabled.

The purpose in hinging the arms 2 and supporting the same by cables 30 is to reduce the shock occasioned by their thrashing down upon the surface of the water as the vessel rocks and plunges in a heavy sea. The shafts 11, 12 are each formed with a universal coupling 33 (Fig. 3) to permit the swinging action of said arms.

I prefer to provide each arm 2 with a pair of horizontal wheels 34 to receive the inward thrust of the chains 7 and 8, especially at the bow and stern of the ship.

I also prefer to provide the chain 8 with several hooks 35 projecting outward therefrom, in order that should the netting 4 come in contact with any anchored or floating mine, the latter will have its chain engaged by one of said hooks and the mine carried around to the stern of the vessel, at which point the motion of the latter will cause the mine to become detached from the hook and caused to drift astern.

What I claim is:

40 1. An apparatus for protecting the body of a ship comprising, in combination, a netting and means for moving said netting longitudinally of the ship while it is in position to protect the surface thereof.

45 2. An apparatus for protecting the sides of ships from torpedoes, comprising a netting and means for moving the same circumferentially of the ship.

3. The combination with a vessel, of a horizontally extended netting, and means for continuously moving the latter horizontally, whereby a torpedo striking the same is laterally diverted.

4. The combination with a vessel, of an endless netting horizontally extended about the vessel, and means for giving a continuous motion of translation thereto.

5. The combination with a vessel, of spaced arms projecting from the sides of the vessel, an endless netting horizontally

extended about the vessel and supported by the arms, and means for longitudinally moving the netting.

6. The combination with a vessel, of spaced arms projecting from the sides of the vessel, sprocket wheels at the ends of said arms, means for forcibly rotating certain of the sprocket wheels, and an endless netting including a chain horizontally extended about the vessel, said chain engaging said wheels.

7. The combination with a vessel, of spaced arms projecting from and pivoted to said vessel's sides to swing vertically, an endless netting horizontally extended about the vessel and supported by the arms, and means for longitudinally moving the netting.

8. The combination with a vessel, of spaced arms projecting from and pivoted to said vessel's sides to swing vertically, a cable supporting each arm in a substantially horizontal position, an endless netting horizontally extended about the vessel and supported by the arms, and means for longitudinally moving the netting.

9. The combination with a vessel, of hollow arms projecting from the sides of the vessel, shafts in said arms having means within the vessel for their forcible rotation, a sprocket wheel fixed upon the outer end of each shaft, an idler wheel carried by each arm immediately in contact with the periphery of each sprocket wheel, and a netting including a chain movable between each provided wheel and idler.

10. A torpedo netting comprising, in combination with a vessel, a series of driven shafts projecting from the sides of the vessel, a flexible coupling connected with the end of each shaft, a shaft connected with each flexible coupling, a tubular arm containing each of the last-named shafts having a ball and socket connection with the vessel and supported in a substantially horizontal position, a sprocket wheel carried by each of the last named shafts, a second sprocket wheel carried by each tubular arm in peripheral contact with the wheel on the associated shaft, a netting, and a sprocket chain passing between the peripheries of each pair of said wheels and supporting the netting.

In testimony that I claim the foregoing invention, I have hereunto set my hand this 8th day of October, 1914.

EWEN A. CLARK.
